UNITED STATES PATENT OFFICE.

HOWARD J. MURPHY, OF READING, MASSACHUSETTS.

LUBRICANT-EXPELLING DEVICE.

Application filed February 11, 1925. Serial No. 8,583.

This invention aims to provide an improved high pressure lubricant-expelling device.

In the drawings, which illustrate a preferred embodiment of my invention:—

Figure 1 is a longitudinal section through a lubricant-expelling gun, being partly in elevation;

Fig. 2 is a longitudinal section through the discharge end of the gun, being partly in elevation and showing the relation of the parts thereof when lubricant is being expelled to a lubricant-receiving nipple shown in elevation; and

Fig. 3 is a front end elevation of the lubricant-expelling device.

Referring to the drawings, I have shown a lubricant-expelling gun which includes means for expelling lubricant under pressure in substantially the same manner and for the same purposes as more fully illustrated and described in my co-pending application Serial No. 8,582, filed herewith, in which co-pending application the invention is more broadly claimed.

The drawings show an improved and simplified arrangement of parts within the discharge end of the gun. These parts may be assembled and disassembled very easily and quickly and are arranged so that they are held together by a single sleeve. The parts are also arranged, as illustrated, so as to withstand the high pressure exerted upon them when lubricant is being expelled from the nozzle to a lubricant-receiving nipple, as illustrated in Fig. 2.

Referring to Fig. 1, I have shown the usual barrel 1, having a rear head 2 into which is threaded a plunger stem 3 carrying the usual plunger 4 and handle 5 at the respective ends thereof. At the front or discharge end of the gun, I have shown a reduced end portion 6, formed integral with the barrel 1 and exteriorly threaded for engagement with the interior threads of a nozzle sleeve 7.

The coupling part or nozzle sleeve 7 presents interiorly thereof, adjacent its outer end, relatively steep pitched threads 8 for engagement with the threads 9 of a lubricant-receiving nipple 10. Beyond the threads 8, I have provided a shoulder 11 against which is seated a centering washer 12, which supports a suitable hat-shaped

sealing washer 13 and also centers and limits the movement of the nozzle of the gun over the lubricant-receiving nipple 10. The coupling threads, nipple, centering washer and hat washer are substantially as shown and more fully described in my co-pending application, Serial No. 616,302, filed February 1, 1923.

Within the nozzle, I have provided a valve-carrying part 14 having a chamber 15 therein of relatively smaller cross-sectional area than the barrel 1. This valve-carrying part fits partly within the reduced end portion 6 of the barrel and is provided with a tapered shoulder 16 seated against the end of the reduced end portion 6. A hollow valve seat part 17 fits between the outer end of the valve-carrying part 14 and centering part 12 and receives the hat washer 13. The part 17 has a tapered end portion 19 seated against the end of the valve-carrying part 14 and a shouldered end portion holding the base 18 of the sealing washer 13 between it and the centering washer 12.

The valve seat part 17 presents a valve seat 21 against which a relatively large closure valve 22 is seated (Fig. 1) to prevent passage of lubricant out of the nozzle except when the closure valve is displaced by the end of the nipple.

At the inner end of the valve-carrying part 14, I have provided a ball check valve 23 and between both valves is a spring 24 normally closing them. The valve seat part 17 is a relatively small part and, when worn to an extent that the closure valve does not prevent leakage, it may be easily and inexpensively replaced, whereas the valve seat part shown in my first-mentioned copending application filed herewith, would be a more expensive replacement part and could not be as easily and quickly replaced.

Heretofore some trouble has been experienced in holding the hat-washer sealing part in place. If the parts that hold the sealing washer are drawn together too tightly, the base portion 18 is apt to be severed from the rest of the washer. To remedy this, I have provided a shoulder 25 at the outer end of the valve seat part against which the base of the washer rests and a relatively thin annular flange portion 26 which surrounds the periphery of the base portion 18 and seats against the centering washer 12.

to limit the amount which the base of the washer may be compressed. Thus the base 18 of the sealing washer 13 can never be squeezed enough for it to be cut away from the remainder thereof.

In assembling the nozzle of the gun with the barrel, the centering washer 12, sealing washer 13, the valve seat part 17, the valves 22 and 23 and valve-carrying part 14 are assembled within the nozzle sleeve 7. The end of the valve-carrying part is then inserted within the reduced end portion 6 of the barrel 1 and the sleeve is screwed over the end portion until the parts are gripped tightly between the end of the reduced end portion 6 and the shoulder 11. The tapered shoulders 16 and 19 provide seals between the parts of the nozzle to prevent lubricant from leaking past the parts where they seat against each other.

Strain upon the parts of the nozzle, due to the pressure of the lubricant, is exerted mainly upon the threads between the sleeve 7 and the reduced end 6 of the barrel 1. As there is a relatively large area of engagement of the threads on these parts, there can be no great danger of destroying the nozzle or any parts thereof, by pressure of the lubricant.

Lubricant may be expelled from the chamber 15 to the lubricant-receiving nipple 10 under a relatively high potential pressure or low potential pressure in the same manner as fully described in my first-mentioned co-pending application filed herewith.

While I have shown and described a preferred embodiment of my invention, it will be understood that changes involving omission, alteration, substitution and reversal of parts, and even changes in the mode of operation, may be made without departing from the scope of my invention, which is best defined in the appended claims.

Claims:—

1. A lubricant-expelling device including a barrel having a reduced end portion formed integral with said barrel, a valve-carrying part having a shoulder abutting the end of said reduced portion, a valve seat part abutting the end of said valve-carrying part, a valve for said valve-carrying part coacting with the valve seat for said valve seat part, a sealing washer and a metal washer beyond said valve seat part and a coupling part presenting a sleeve secured to the reduced end portion of said barrel for holding all of said parts in assembled relation with said barrel.

2. A lubricant-expelling device including a barrel having a reduced end portion formed integral with said barrel, a nozzle sleeve threadedly secured to said reduced end portion, coupling means adjacent the end of said sleeve, a shoulder presented by said sleeve inwardly of said coupling means;

a metal washer, a flexible sealing washer, a valve seat part and a valve-carrying part all held in assembled relation with said barrel, between the end of said reduced portion and said shoulder, by said nozzle sleeve, and a valve for said valve-carrying part coacting with said valve seat.

3. A lubricant-expelling device including a barrel having a reduced end portion formed integral with said barrel, a valve-carrying part having a tapered shoulder seated against the end of said reduced portion, a valve seat part having a tapered shoulder seated against the end of said valve carrying part, a valve for said valve-carrying part coacting with said valve seat, and a nozzle sleeve secured to said reduced end portion and holding said tapered shoulders tightly against their seats to provide seals against escape of lubricant between said parts.

4. A lubricant-expelling device including a nozzle having a nozzle sleeve presenting coupling means at the outer end thereof for engagement with a lubricant-receiving nipple, means forming a shoulder on said sleeve inwardly of said coupling means, a flexible hat washer for engagement with the lubricant-receiving nipple to provide a tight seal between the nipple and said nozzle, a valve seat part presenting a recessed end having a shoulder squeezed against the base of said hat washer for holding the latter in place, said recessed end of said valve seat part providing means to prevent said valve seat part from severing the base of said hat washer from the remainder thereof when squeezed thereagainst, and a valve coacting with said valve seat part.

5. A lubricant-expelling device including a nozzle having a nozzle sleeve presenting coupling means at the outer end thereof; a centering part, a flexible sealing washer and a valve seat part within said sleeve inwardly of said coupling means; said sealing washer presenting a flat base portion held between said centering part and the outer end of said valve seat part, means presented at the outer end of said valve seat part to prevent cutting of the base portion of said washer when squeezed between the end of said valve part and said centering part, and a valve coacting with said valve seat part.

6. A lubricant-expelling device including a nozzle having a nozzle sleeve presenting coupling means at the outer end thereof; a centering part, a flexible sealing washer and a valve seat part within said sleeve inwardly of said coupling means, a valve coacting with said valve seat part; said sealing washer presenting a flat base portion held between said centering part and the outer end of said valve seat part, and an annular part surrounding the periphery of the base of said sealing washer to limit the amount which the base of

said sealing part may be compressed between said centering part and the end of said valve seat part.

7. A high pressure lubricant-expelling device comprising, in combination, a barrel presenting a reduced end portion, means for expelling lubricant from said barrel, a valve carrying part partly located within the reduced end portion of said barrel, a valve seat part seated against the end of said valve carrying part, a coupling sleeve secured to the reduced end of said barrel for holding said valve seat part and said valve carrying part in assembled relation with said barrel, a relatively large closure valve seated against said valve seat part adjacent the outer end of said valve carrying part, a check valve located at the inner end of said valve carrying part, a spring interposed between said valves, and means forming a chamber between the seats for said valves, from which lubricant may be expelled under a relatively higher pressure than the lubricant may be expelled from said barrel.
8. A high pressure lubricant-expelling device comprising, in combination, a barrel presenting a reduced end portion, means for expelling lubricant from said barrel, a valve carrying part partly located within the reduced end portion of said barrel, a valve seat part seated against the end of said valve carrying part, a coupling sleeve secured to the reduced end of said barrel and holding said valve seat part and said valve carrying part in assembled relation with said barrel, a chamber within said valve carrying part having a relatively smaller cross-sectional area than said barrel, a check valve located between said chamber and said barrel to permit flow of lubricant only from said barrel to said chamber, and a closure valve and means associated therewith for holding the same normally seated against said valve seat part adapted to be opened by the end of a lubricant receiving nipple to permit passage of lubricant from said chamber to the nipple.
9. A high pressure lubricant expelling device comprising, in combination, a barrel presenting a reduced end portion, means for expelling lubricant from said barrel, a valve carrying part partly located within the reduced end portion of said barrel, a valve seat part seated against the end of said valve carrying part, a coupling sleeve secured to the reduced end of said barrel and holding said valve seat part and said valve carrying part in assembled relation with said barrel, a chamber within said valve carrying part having a relatively smaller cross-sectional area than said barrel, a check valve located between said chamber and said barrel to permit flow of lubricant only from said barrel to said chamber, a closure valve and means associated therewith for holding the same normally seated against said valve seat part adapted to be opened by the end of a lubricant receiving nipple to permit passage of lubricant from said chamber to the nipple.
10. A lubricant-expelling gun having a barrel provided with manually operated displacement means for forcing lubricant therefrom, a coupling means for connecting said barrel to a nipple, conduit means connecting said barrel and coupling means, spaced valve seats for said conduit means, valves for said seats, and a single spring for urging said valves toward their seats, one valve permitting flow of lubricant only from said barrel toward said coupling means and the other being opened by the nipple when operatively engaged by said coupling means.
11. A lubricant-expelling gun having a barrel provided with manually operated displacement means for forcing lubricant therefrom, a coupling means for connecting said barrel to a nipple, conduit means connecting said barrel and coupling means, spaced valve seats for said conduit means, valves for said seats, and a single spring for urging said valves toward their seats, one valve permitting flow of lubricant only from said barrel toward said coupling means and the other being opened by the nipple when operatively engaged by said coupling means.
12. A lubricant-expelling gun having a barrel provided with manually operated displacement means for forcing lubricant from said barrel, a cup shaped member the bottom wall of which is perforated to receive the lubricant expelled from said barrel, a part having a perforation closing the opposite end of said member, a pair of valves in said member, a spring engaging said valves for urging them to seat respectively on said bottom wall and on said part for normally closing the perforations in said bottom wall and part, a coupling for connection to a nipple, said nipple when operatively engaged by said coupling opening said valve normally seated on said part.
13. A lubricant-expelling gun having a barrel provided with manually operated displacement means for forcing lubricant from said barrel, means forming a chamber having a port at one end for receiving the lubricant expelled from said barrel and a port at the opposite end for exit of lubricant from said chamber, means forming valve seats associated with said ports, a pair of

4
valves in said chamber, a single compression spring engaging said valves and urging them toward said seats for normally closing said ports, a coupling means forwardly of said chamber for connection to a nipple, said nipple when operatively engaged by said coupling means opening the valve normally closing the exit port of said chamber.

14. A lubricant-expelling gun having a barrel provided with manually operated displacement means for forcing lubricant from said barrel, means forming a chamber having at opposite ends a valve controlled inlet port for receiving the lubricant ex-

15
pelled from said barrel and a valve controlled exit port for the lubricant expelled from said chamber, relatively movable valves for said ports, a single compression spring in said chamber urging said valves toward closed position, coupling means forwardly of said chamber for connection to a nipple, said nipple when operatively received by said coupling means positively opening the valve controlling said exit port.
